[57] CLAIM

The ornamental design for a computer peripheral, as shown and described.

DESCRIPTION

FIG. 1 is a perspective view of a computer peripheral showing our new design;

FIG. 2 is a front elevational view thereon;

FIG. 3 is a rear elevational view thereof;

FIG. 4 is a right side elevational view thereof, the opposite side being a mirror image;

FIG. 5 is a top plan view thereof;

FIG. 6 is a front elevational view of a second embodiment of our design; and

FIG. 7 is a side elevational view thereof, the opposite side being a mirror image.

The rear and top of the second embodiment are identical to the rear and top of the first embodiment.
